FUEL INJECTION SYSTEM

Ferdinando Carlo Reggio, Detroit, Mich., assignor
to Caterpillar Tractor Company, Peoria, Ill.

Application July 20, 1940, Serial No. 346,479

19 Claims. (Cl. 123—139)

This invention relates to a fuel supply system for internal combustion engines and in particular to a fuel injection system for intermittently delivering liquid fuel under pressure and in measured quantities into the cylinders or into the induction manifold of the engine. More specifically, the invention relates to fuel injectors, including a fuel injection nozzle and a fuel pump mounted close together in a single housing or body so as to eliminate the necessity of having a long fuel line therebetween. Such lines containing a column of fuel of considerable volume in relation to the volume of fuel discharged at each cycle by the pump and having a considerable length are particularly objectionable in high-speed engines and in engines in which the fuel is injected at high pressure, because the pressure surges and the effect of the fuel compressibility therein, may adversely affect the accuracy of the injection timing and the discharge characteristics of the nozzle.

Fuel injectors including an injection nozzle and a fuel pump arranged coaxially in a single body have long been used. The pump is usually provided with a reciprocating plunger actuated from the engine camshaft by means of a tappet or reciprocating mechanism. One drawback of this arrangement is that the injector cannot be removed from the engine and replaced without disassembling the tappet mechanism. Furthermore, the injection timing has usually to be readjusted every time that the injector is replaced.

To obviate these disadvantages a desirable arrangement consists of an injector unit including an injection nozzle element and a fuel pump element, said elements being mounted not coaxially but at an angle relatively to one another. This angle may vary according to the specific requirements of the engine. The injector may thus be mounted to one side of the engine cylinder where it is particularly accessible and may be easily removed and be replaced without disassembling any parts of the engine, such as the reciprocating mechanism therefor, and the valve gear mechanism, and where it may be actuated from the engine camshaft by means of a simple, compact, and inexpensive tappet mechanism.

One of the object of the invention is to provide a fuel system including an improved injector of the character described, composed of a relatively small number of parts, easily machinable, and which may be readily assembled; which is economical to manufacture, and in which the accurately machined parts, such as the pump barrel and the pump plunger are arranged

and connected with the cooperating elements of the injector so as to eliminate the danger of distortion thereof.

Another object is to provide means for attaching the injector to the engine, whereby the injector may be easily mounted and removed therefrom, and whereby the timing adjustment of the injection may be facilitated, or the necessity of such an adjustment may be eliminated.

A still further object is to provide in an internal combustion engine a fuel injection system including interchangeable injectors of the character described which are mounted out of the zone of high temperatures from the combustion chamber; which are enclosed in the engine housing and readily accessible for inspection and replacement, and which may be actuated from the engine camshaft by means of inexpensive and compact reciprocating mechanism, whereby permitting an appreciable reduction in the cost and overall dimensions of the engine.

The above and other objects of the invention will be apparent as the description proceeds; and while I have illustrated and described the preferred embodiments of the invention as they now appear to me, it will be understood that such changes may be made as fall within the scope of the appended claims. In the following description and in the claims various details will be identified by specific names for convenience, but they are intended to be as generic in the application as the art will permit. The drawings show various embodiments of my invention.

Figures 1 to 4 show one form of injector of my invention in which the nozzle is of the open type arranged at right angles with the axis of the pump. Figure 1 is an elevational view; Figures 2 and 3 are sections taken in planes indicated by lines 2—2 and 3—3 in Figures 1 and 2 respectively. Figure 4 is a side elevational view.

Figure 5 shows, part in section and part in elevational view, another form of injector having a nozzle of the open type.

Figures 6 and 7 show another form of injector having a closed or differential type of nozzle. Figure 7 is a section taken in a plane indicated by lines 7—7 in Figure 6.

Figures 8 to 10 show another form of injector having a closed-type nozzle. Figures 9 and 10 are sections taken in planes indicated by lines 9—9 and 10—10 respectively in Figure 8.

Figure 11 shows a still different form of injector provided with a nozzle of the closed type. Figure 12 is a sectional elevation of the mecha-

nism of my invention including an injector in association with an engine.

Figures 13 and 14 are fragmentary elevational views of a detail included in Figure 12.

Figures 15 to 17 are sectional elevations showing the mechanism of my invention including an injector in association with engines of various types.

Referring to Figures 1 to 4, the injector forming part of the invention includes a body or housing 22 in which is removably mounted a pump barrel 24 provided with a fuel inlet port 26. A pump plunger 28 is mounted in barrel 24 and is adapted to be reciprocated from an engine driven cam by a tappet mechanism 30. The plunger may be of any suitable construction, preferably of the type in which the volume of fuel injected by the pump may be controlled by angular adjustment of the plunger about its axis. Such type of construction which usually includes annular groove 32 communicating with the pressure chamber 34 at the inner end of the plunger through an axial groove 38, and provided with at least one inclined scroll edge 36 for covering and uncovering the fuel inlet port 26, is well-known in the art and it is therefore considered unnecessary to describe it in detail. A cap screw 40 engaging a slot machined in the barrel 24 holds the latter against rotation. Plunger 28 is slidably but non-rotatably mounted in pinion 42 which engages a rack 44 reciprocable in a bore of body or housing 22, so that an axial movement of the rack causes a rotation of plunger 28 and in turn a variation of the delivery of the injector. A spacer 45 having a central fuel passage is mounted at the inner end of barrel 24. The housing 22 of the injector is provided with a passage 46 formed at right angles with the axis of plunger 28 and in which is mounted a fuel conduit member 48 held in proper angular position by means of a dowel 50 engaging a slot formed in the wall of passage 46. The outer end of conduit member 48 is seated against the end of the wall of passage 46, while the inner end thereof is provided with a head 51 adapted to seat against spacer 45 and formed with a cavity containing a check or non-return valve 52. The central or intermediate portion of conduit member 48 is formed with a narrow section so as to be resilient and to yield within designed limits.

Against the outer end of such conduit member 48 is mounted the nozzle tip member 53 held by means of cap 54 screwed onto the wall of passage 46. A spring-loaded, non-return valve 56 is provided between the fuel conduit member 48 and nozzle tip member 53; and a duct axially drilled in the latter leads fuel to the discharge orifice 57. The head 51 at the inner end of fuel conduit member 48 and the spacer 45 are held against the barrel 24 by means of a spacer 58, kept from rotating by a screw and groove connection 59, which in turn is clamped by a screw plug 60. An annular seal 61 interposed therebetween prevents leakage of fuel past the screw plug.

All the parts of the injector may be very easily assembled or taken apart. In assembling, rack 44 is mounted in its bore; pinion 42, plunger 28, barrel 24 and spacer 45 may be introduced from the top in body 22; then the conduit member 48 is mounted endwise through passage 46 and clamped therein by means of nozzle tip member 53 and cap 54. It will be realized that however accurate the machining of the various parts involved may be, the head 51 of the inner part of conduit member 48 will hardly be in contact with spacer 45 at all points of its designed surface, but said contact will more likely be limited to some peripheral por-

tion thereof, hence, when the head 51 is clamped against spacer 45 by means of spacer 58 and screw plug 60 deformation of some element of the injector structure will necessarily occur. Since the intermediate portion of conduit member 48 is made of comparatively narrow cross section, this portion will yield, that is bend, or twist, or both, without opposing any appreciable reaction that, transmitted to the barrel 24, might cause the latter to bend, thereby adversely affecting the operation of the pump.

The plunger 28 is formed with a head 62 and a groove 63 adjacent the outer end thereof adapted to provide a head and T-slot detachable connection with a tappet mechanism 30.

Fuel enters the injector through an inlet 66 communicating with port 26 of barrel 24, and excess fuel flows through groove 67 machined in barrel 24 to passage 46 and leaves the injector through outlet 68 connected with passage 46. This flow of fuel, determined by a difference of pressure between fuel inlet 66 and fuel outlet 68, vents the injector of all bubbles of air, vapor or gas that separate from the fuel, and which, if it were permitted to reach the pressure chamber 34 through port 26, might interfere with the correct operation of the pump. Such flow also cools the various parts of the injector.

It is important that the injector be firmly attached to the engine and held in an accurately determined position relative to the tappet or reciprocating mechanism. To that end the injector 22 is formed with a flange 70 extending in a plane normal to the axis of the nozzle and which has spaced holes 71 for receiving, guiding and centering dowels 72, and spaced holes 74 for receiving securing cap screws or studs 75.

The dowels 72, permanently secured to the engine and having accurate close fit in the holes 71, hold the injector 22 centered in the proper position relative to the operating cam and reciprocating mechanism, and prevent the injector from being misaligned due to the thrust imparted thereto by the load applied to the plunger 28 by the tappet 30. Furthermore, since the dowels 72 are perpendicular to the axis of the plunger 28 and the latter is centrally located relatively to the flange 70, no appreciable distortion or deformation of body 22, and in particular no bending of the walls of passage 46 may occur. The cap screws or studs 75 parallel to the dowels 72 pass with radial clearance through apertures 74 and have a threaded connection with a suitable part of the engine structure. They hold the nozzle gasket 76 or other equivalent sealing means clamped against a shoulder provided in the engine as it will be disclosed later in detail.

A further embodiment of the invention is illustrated in Figure 5 in which the injector body or housing 80 is provided with a nozzle member 81 mounted at right angles with barrel 24 and having a fuel passage therein in communication with the nozzle discharge orifice 57. A wedge-shaped member 82 is adapted to be clamped simultaneously against the adjacent plane surfaces of spacer 45 and nozzle member 81 by means of a wedge-shaped spacer 84 held from rotation by a screw and slot connection 85 and clamped by screw plug 60. When the latter is tightened a load is transmitted by spacer 84 to member 82. The resultant of said load is applied to member 82 approximately at the point of intersection of the axis of the barrel 24 and nozzle member 81, and is therefore decomposed in two component loads substantially coaxial with said barrel 24 and said nozzle 81, thereby eliminating the

danger of distortion or asymmetric deformation thereof. Member 82 has a fuel duct 86 therein to establish fuel communication between barrel 24 and nozzle member 81. Check valve 52 and spring-loaded non-return valve 56 are provided. This nozzle is otherwise similar to that disclosed in connection with Figures 1 to 4 and it is therefore regarded unnecessary to again describe it in detail.

The nozzles of the previously described injectors are of the open type. In Figures 6 and 7 is illustrated a modified form of injector in which the nozzle is of the closed or differential type. Most points of such injector are similar to those already described in the foregoing. Injector 10 housing or body 120 includes a pump barrel 24 clamped in position by means of a screw plug 60 bearing against spacer 121, which in turn bears against inner head 122 of conduit member 123, such conduit member having a narrow resilient 20 intermediate portion 124 extending through nozzle passage 125 providing a fuel cooling chamber. A nozzle tip member 128 seats against the outer surface of conduit member 123 and is clamped in position by cap 54, a pin and slot connection 25 130 serving to hold conduit member 123 in proper angular adjustment relative to body 120. Nozzle tip member 128 includes an axially reciprocable needle valve 132 controlling the flow of fuel to the discharge orifice 133. A rod 134 extending with radial clearance through an opening provided in spacer 121 and through passage 125 transmits the load of spring 135 to needle valve 132. Adjustable stop 136 serves to limit the lift of needle valve 132, and a threaded cap 137 is provided to adjust the load of spring 135 and thereby determine the fuel pressure at which the valve 132 opens to allow delivery of fuel through to the orifice 133. The entire spring assembly is enclosed by a cap 138.

Fuel enters the injector through the fuel inlet line 140 detachably connected therewith. Excess fuel and leakage fuel that might flow past the needle valve 132 collects into passage 125 and is led back to the source through a fuel return line 141 thereby venting and cooling the injector 128. While the mechanism for controlling the angular adjustment of the pump plunger might be similar to those previously described, a slightly modified construction is shown in Figures 6 and 7 in which a split gear sector 143 is secured to pump plunger 144 by means of screw 145 and thus reciprocates with the plunger. A rack 147 slidably mounted in notches formed in extensions carried by housing 120 and held by a detachable retaining member 148 engages with gear sector 143 whereby axial reciprocation of rack 147 results in angular adjustment of plunger 144. The lower end of retaining member 148 is adapted to prevent the plunger 144 from being dropped while the injector 120 is not mounted on the engine and the plunger 144 not connected with the tappet mechanism. Also a slightly different arrangement of check valve is shown in Figure 7 in which valve 150, enclosed in suitable chamber formed in inner end 122 of conduit member 123, rests directly on pump barrel 24, thus eliminating the necessity of having an intermediate spacer similar to that indicated by number 45 in some of the drawings previously referred to.

The modification illustrated in Figures 8 to 19 differs from that of Figures 6 and 7 in that the spring 152 loading the needle valve 132 reciprocable in nozzle tip member 128 is contained in a cavity provided in fuel conduit member 154

5 mounted in passage 155 formed in injector housing 156. Such fuel conduit member 154 has an inner head 157 between spacers 45 and 58, and an outer seating part 158 clamped between nozzle tip member 128 and the walls of passage 155 by means of cap 54 and joined to head 157 by means of two integrally connected spaced arms 159 between which spring 152 is mounted. One of said arms has a fuel duct 160 therein connecting the check valve 52 with the needle valve 132. A spacer 162 serves to limit the lift of needle valve 132. Arms 159 forming the intermediate portion of conduit member 154 have a small section and are thus highly resilient, whereby conduit member 154 may bend or twist as it has already been disclosed in detail in connection with the injector of Figures 1 to 3, without opposing appreciable reactions tending to bend the pump barrel 24.

A still further modification is indicated in Figure 11 showing an injector 165 substantially similar to injector 80 of Figure 5 but having a nozzle of the closed or differential type including a nozzle tip member 166 having a reciprocable needle valve 132 therein loaded by spring 167 contained in the spring cage 168 provided with a fuel duct 169 connecting check valve 170 with needle valve 132. A wedge-shaped member 172 is adapted to be clamped simultaneously against barrel 24 and spring cage 168, the latter being thrust against nozzle tip member 166 axially held by split ring 173. A packing ring 174 prevents fuel leakage about the nozzle tip member 166.

Figure 12 illustrates the mechanism of my invention in association with an internal combustion engine of the compression-ignition or Diesel type having a cylinder 180 with a piston 181 reciprocable therein and a precombustion chamber 182 mounted in a suitable cavity provided in the engine block 183 at one side of the cylinder 180 and surrounded by a cooling water jacket 184. Chamber 182 is connected through a passage 185 with cylinder 180, held in proper angular position relative thereto by a pin and groove connection 186, and clamped in position by the engine head 188 resting on the engine block 183 with the usual cylinder head gasket 189 interposed between the block and the head.

A sleeve 190 traversing the outer and inner walls of the water jacket 184 and the wall of the precombustion chamber 182 is provided with passage 191 extending from the chamber 182 to the injector compartment 192 and is adapted to receive the nozzle part 193 of an injector 194 which may be similar to any of the previously described injectors, preferably of the type in which the axis of the nozzle and of the pump are perpendicular, such as in the examples shown in Figures 1 to 5 and 6 to 11 of the drawings.

60 Sleeve 190 has a shoulder 196 against which the nozzle tip seating part, such as sealing gasket 197 mounted at the end of the nozzle part 193, is adapted to be thrust by attaching means, for example, two studs 75 parallel to the axis of the nozzle 173 and secured to the wall 198 of the engine block 183, and nuts 199. Spaced dowels 72, also parallel to the axis of nozzle 193 and fixedly secured to the wall 198 of the engine block 183, are adapted to be received with accurate fit 65 in holes 74 (shown in Figure 1) of flange 70 of injector, thus centering and holding the latter in a predetermined position. Radial clearance is provided between nozzle part 193 of the injector 194 and sleeve 190 and between attaching studs 75 and receiving holes 74 therefor made in flange

70 of injector 194 so as to avoid any binding when the injector is clamped in position.

Axial reciprocation of rack 44 and thereby angular adjustment of pump plunger 28 of injector 194 is effected through a governor-controlled fuel control mechanism which comprises a rod 201 parallel to rack 44 slidably mounted in brackets 202 carried by engine wall 198, and a connecting arm 203 secured to rod 201 and extending perpendicularly from such rod to engage a slot formed in rack 44. Since the latter is mounted in housing of injector 194 for axial reciprocation in a direction which is at right angles with guiding and centering dowels 72, and that portion of connecting arm 203 which engages rack 44 is parallel to such dowels, it is clear that variations in the position of injector 194 such as might be caused by changes in the thickness of nozzle gasket 197 do not alter the position of rack 44 relative to injector 194 and therefore do not affect the fuel delivery thereof.

A camshaft 205 is supported in bearings carried by the engine block 183 and serves to actuate through push rods 206 the inlet and exhaust valves, not shown in the drawings, mounted in the head 188 of engine. Any suitable tappet mechanism for actuating the plunger 28 of injector 194 from said camshaft may be provided. A convenient arrangement, shown in Figure 12, includes a cam follower of the mushroom type 208 reciprocably mounted in a bearing 209 carried by the engine block 183 and provided with a cavity therein containing lower and upper seat members 211 and 212 respectively urged against one another and against the end of said cavity by the lower end of the coil spring 213, the upper end of which is seated against collar 214 held by retaining ring 215 mounted in a groove formed in bearing 209.

A tappet rod 217 is provided at its lower end with an expanded head 218 held with small clearance between seat members 211 and 212, while at its upper end it carries a connecting member 220 attached to said rod by means of a threaded connection and a lock nut 221. Such connecting member 220 includes a head 222 formed with a T-shaped slot 223 having a close fit with a head 224 and a groove 225 formed at the lower end of pump plunger 28. A U-shaped retaining member 227 slidably mounted about connecting member 220 is upwardly urged by a spring 228 to laterally close the T-shaped slot 223 and eliminate the danger that the head 224 of plunger 28 may be accidentally disconnected from connecting member 220. Said retaining member 227 is shown in its operating position in Figure 13, while Figure 14 shows such retaining member as it is being held against the load of spring 228 in a position in which tappet rod 217 may be disconnected from pump plunger 28.

It is therefore clear that tappet rod 217 is centered at its lower and upper ends by the cam follower 208 and by the pump plunger 28 respectively, thus eliminating the necessity of providing guiding or supporting means therefor, and furthermore, it may be readily detached from the pump plunger 28. Thus, spring 213 holding cam follower 208 in contact at all times with the cooperating cam carried by camshaft 205 also effects the return or suction stroke of the pump plunger 28 of injector 194.

In the preferred embodiment of the invention the cam follower 208 and the tappet rod 217 are coaxial or substantially coaxial with the pump plunger 28 of the injector 194; hence, slight

changes in the position of injector 194 compatible with the centering action of dowels 72, that is slight variation in the position of the injector along the axis of the nozzle part 193 which is at right angles with the pump plunger 28, such as might be caused by changes in the thickness of nozzle gasket 197, do not cause any appreciable modification in the adjustment of pump plunger 28 relative to dowel 24 and therefore do not affect the timing of the injection. Furthermore, it is to be noted that in the example of Figure 12 both the centering dowels 72 for the injector 194 and the bearings of the camshaft 205 are supported by the engine block 183. According to the invention the distance therebetween, the radii of the cam, and the length of the tappet mechanism are all accurately kept within close predetermined tolerances; the result being that when the camshaft 205 is in a given angular adjustment, for example corresponding to the point of minimum lift of the tappet mechanism, the T-shaped slot 223 of the connecting member 220 thereof and in turn the head 224 of pump plunger 28 are within a close predetermined tolerance at a definite distance from the guiding and centering dowels 72. Preferably, the various elementary parts included in the tappet mechanism which determine the total length thereof are machined within strict tolerances so that they are interchangeable and may be individually replaced without modifying the position of pump plunger 28 relative to the dowels 72.

In injector 194, when the head 224 of pump plunger 28 is at a definite distance from the receiving holes 71 for the centering dowels 72, that portion of the plunger 28 which is adapted to cover and uncover the inlet port 26, and thus controls the injection, is at corresponding predetermined axial distance from said port 26, whereby all injectors 194 are interchangeable and may be replaced without affecting the injection timing.

It may be shown that slight variations in the lengths of the various parts of the tappet mechanism and of the injector within reasonable manufacturing tolerances cause variations in the injection timing that usually are considerably smaller than one degree of crank shaft rotation. Injection timing is therefore far more accurate than with the conventional injection system including separate injection nozzle and fuel pump interconnected by a comparatively long high-pressure fuel line wherein pressure surges and fuel compressibility adversely affect the injection characteristic.

The injection compartment 192 is enclosed by a cover 230. Fuel is led to the injector and the excess thereof is returned to the source through fuel lines detachably connected with the injector such as that indicated by 231 in Figure 12. From the foregoing it will be appreciated that the injector 194 may be readily inspected and replaced, which is important not only in manufacturing but also in servicing in the field. In order to replace the injector 194 it is sufficient to remove cover 230, disconnect fuel lines 231 from the injector, disconnect the tappet mechanism 217 from the pump plunger 28 while the retaining member 227 is being held in the position indicated in Figure 14, and remove nuts 199, whereupon the injector may be withdrawn.

Since all parts are enclosed within the engine block and therefore protected from dirt, dust, and water, thus eliminating all danger of oxidation, the foregoing operations may be readily accom-

plished. The inverted operations are made when the injector is mounted on the engine: in doing so the groove formed in rack 44 may be easily engaged with connecting arm 203 carried by rod 201.

While in the arrangement of Figure 12 both the camshaft and the precombustion chamber are located in the engine block, the modification indicated in Figure 15 shows an engine in which the camshaft 205 is supported in the engine block 234, but in which the precombustion chamber 236 is located in the cylinder head 237 clamped on the engine block with the usual cylinder head gasket 238 interposed therebetween. In such type of engine an injector 194 which may be similar to any of the previously described injectors is provided to inject fuel into the precombustion chamber 236 thereof. As previously stated, it is important that the distance from the cam profile on camshaft 205 to the guiding and centering dowels 72 be held within close limits in order to obtain correct timing of the injection. However, variations in the initial thickness of gasket 238 and in the degree of compression thereof when clamped between head 237 and block 234 cause changes in the distance therebetween. Thus, instead of securing the guiding and centering dowels 72 to the cylinder head 237, they are carried at a closely determined distance from the camshaft by suitable supporting means accurately positioned on the engine block 234. The bracket 240 centered on cylinder block 234 by means of dowel pins 242 and secured thereto by studs threaded into the block and nuts 243, has spaced upwardly extending arms 244 in which the guiding and centering dowels 72 have a press fit. The injector 194 is guided and centered by said dowels, while studs 246 secured in the cylinder head 237 and passing with suitable radial clearance through openings 74 of flange 70 and nuts 199 having a threaded connection therewith are provided for clamping the injector 194 so that the sealing gasket 197 mounted on the nozzle part 193 thereof is thrust against shoulder 248 adjacent combustion chamber 236. Nozzle part 193 is mounted in the cylinder head with radial clearance so as to avoid any binding as the injector is clamped in position.

Any suitable tappet mechanism may be provided for actuating the pump plunger 28 from the camshaft 205. In the embodiment of the invention shown in Figure 15 the tappet mechanism includes a cam follower 250 provided with a roller 252 and mounted for axial reciprocation in a bearing provided in bracket 240. A spring 254 maintains roller 252 at all times in contact with the cam. The upper end 30 of cam follower 250 connected with pump plunger 28 is similar to that shown in Figure 2, and since the cam follower 250 is guided and maintained at all times coaxial with pump plunger 28, no retaining member similar to that indicated by numeral 227 in Figures 12 to 14 is required. Injector rack 44 is controlled by arm 203 secured to rod 201.

Tappet mechanism for actuating intake and exhaust valves mounted in cylinder head 237 (not shown) from camshaft 205 may be provided, including cam followers guided in suitable bearings formed in bracket 240 and tappet rods 206.

It will be apparent that the accuracy of the injection timing, the elimination of the timing adjustment and the interchangeability and accessibility of the various parts of the modification shown in Figure 15 are similar to those described

in detail in connection with the arrangement illustrated in Figure 12.

In the foregoing, two examples have been disclosed in which the engine camshaft is supported in bearings carried by the engine block, fuel being injected either in the engine block or in the cylinder head, the arrangement being such that the injectors may be replaced without requiring timing adjustment of the injection. According to the invention the same result may be obtained when the camshaft from which the injector is actuated is supported in bearings carried by the cylinder head, the fuel being injected either in the cylinder head or in the cylinder block, the essential necessary condition being that the centering dowels for the injector be accurately held at a predetermined distance from the camshaft.

In the foregoing, injectors have been described in combination with liquid-cooled internal combustion engines of the type generally referred to as compression-ignition, or Diesel engines. It is to be clearly understood that according to the invention the injectors may be used in combination with any suitable type of internal combustion engine including both spark-ignition and compression-ignition engines, the latter having either direct injection or precombustion chamber. Furthermore, the injectors may discharge the liquid fuel not only in a precombustion chamber or in the main combustion chamber of the engine cylinder but also in the engine induction system, for instance in the engine intake manifold of a spark-ignition engine ahead of the intake valve. Figure 16 illustrates, as an example, the application of an injector 280 discharging fuel into the combustion chamber 282 of an air-cooled engine having a cylinder head 284 secured to the engine cylinder 286. Such air-cooled engine may be either of the spark-ignition or of the compression-ignition type. Injector 280, which may be provided with cooling fins 288, may be similar to any of the previously described injectors. It may be mounted on the cylinder head 284 by means of guiding and centering dowels 290 secured thereto and having at their outwardly extending end a threaded connection with the nuts 292 serving for clamping the injector 280 on the cylinder head 284 with the usual nozzle gasket 296 interposed therebetween or equivalent sealing means. Fuel lines, not shown, are provided for detachable connection with the fuel inlet 298 and fuel return port of the injector. A control linkage, also not shown in the drawings, is provided for controlling the rack 44 of the injector. The tappet mechanism operating the pump plunger 28 from a suitable cam is shown similar to that described in connection with Figures 12 to 14 and is enclosed by a tubular member 300 as it is customary in aviation engines of the radial type. Injector 280 may be of the design in which the nozzle part thereof is at right angles with the pump plunger 28 and the arrangement may be such that the tappet mechanism is coaxial with the plunger 28, in which case if the distance between the dowels 290 and the cam profile is kept within close limits no timing adjustment is required, as it has been pointed out in connection with the arrangement of Figures 12 to 15. Or, as it is shown in Figure 16, the angle between the nozzle part of injector 280 and pump plunger 28 thereof may be slightly larger than 90 degrees, in which case if the thickness of gasket 296 is kept within close limits the injector 280 may still be replaced without requiring readjustment of injection timing thereof.

Figure 17 shows the application of injector 280 to a spark-ignition engine having a combustion chamber 304 in the cylinder head 306 thereof communicating through port 308 controlled by intake valve 310 with manifold 312. Injector 280 intermittently discharges liquid fuel in said manifold 312 ahead of valve 310. Usually when fuel is injected in the manifold of spark-ignition engines the duration of the injection is considerably longer than when the fuel is injected in the engine cylinder or in the precombustion chamber thereof; and the timing of the injection need not be as accurate.

These embodiments of the invention have been shown merely for purpose of illustration and not as a limitation of the scope of the invention. It is therefore to be expressly understood that the invention is not limited to the specific embodiments shown but may be used in various other ways, and various modifications may be made to suit different requirements, and that other changes, substitutions, additions, and omissions may be made in the construction, arrangement, and manner of operation of the parts within the limits or scope of the invention as defined in the following claims.

What I claim is:

1. An interchangeable fuel injector unit for internal combustion engine including a delivery nozzle body and a plunger pump mounted in said unit transversely with respect to one another; means independent of said nozzle body for guiding and centering said injector unit on said engine; and fuel control means in said injector unit including cooperating rack and gear for controlling the angular adjustment of the plunger of said pump, said rack having its axis in a plane normal to the axis of said plunger and to the axis of said nozzle body.

2. In combination with an internal combustion engine, a fuel injector therefor including housing means, a plunger pump and a nozzle valve mounted therein with their axes at right angles; an engine-driven cam; a tappet mechanism for imparting a reciprocating motion of constant stroke to the plunger of said pump from said cam; and guiding means at opposite sides of said plunger for centering said injector with respect to said engine whereby said injector is mounted thereon and removed therefrom with a movement of translation in the direction of the axis of said nozzle valve without necessitating disassembling of said tappet mechanism.

3. In combination with an internal combustion engine, a fuel injector unit therefor including a nozzle valve part and a plunger pump part mounted therein with their axes at right angles; an engine-driven cam; guiding means independent of said nozzle valve part for centering said injector with respect to said engine at a predetermined distance from said cam; and a tappet mechanism including a tappet rod substantially coaxial with said pump for imparting a reciprocating motion of constant stroke to the plunger thereof from said cam.

4. In combination with an internal combustion engine, an interchangeable fuel injector therefor including an injection nozzle valve and a pump having their axes at right angles; said pump including a cylinder having port means and a plunger reciprocable in said cylinder and controlling said port means; an engine-driven cam; tappet mechanism for transmitting a reciprocating motion of constant stroke to said plunger from said cam; and cooperating means in said

engine and injector including centering dowels whereby said injector is guided in the direction of the axis of said nozzle and centered on said engine in a predetermined position relative to said tappet mechanism whereby said injector may be replaced without requiring adjustment of the injection timing thereof.

5. In combination with an internal combustion engine, an interchangeable fuel injector therefor including a delivery nozzle valve and a plunger pump mounted therein with their axes at right angles, said injector being adapted to be clamped on said engine with sealing means interposed between said nozzle valve and said engine; an engine-driven cam supported in bearings carried by said engine; tappet means in said engine for actuating said injector from said cam; and dowels carried by said engine and cooperating with bores formed in said injector for holding the latter with the axis of said nozzle valve at a definite distance from said cam whereby said injector may be replaced without requiring adjustment of the injection timing regardless of changes of initial dimensions and deformations of said sealing means.

6. In combination with an internal combustion engine, an interchangeable fuel injector therefor including an injection nozzle provided with a delivery valve and a plunger pump; said nozzle and the plunger of said pump being substantially at right angles; said injector being mounted on said engine with sealing means interposed between said nozzle and said engine; means including a rod substantially coaxial with said plunger for reciprocating said plunger from an engine-driven cam; centering means for guiding said injector with respect to said engine in the direction of the axis of said nozzle; fuel control means carried by said injector and including cooperating rack and gear for controlling the angular adjustment of the plunger of said pump, said rack having its axis in a plane normal to the axis of said nozzle and a detachable connection at right angles with control means carried by said engine, whereby changes in the position of said injector relative to said engine in the direction of the axis of said nozzle due to variation of the dimensions of said sealing means affect neither the delivery of said injector nor the injection timing thereof.

7. In combination with an internal combustion engine, an interchangeable injector having housing means; a fuel delivery nozzle and a plunger pump mounted in said housing means transversely with respect to one another; centering means carried by said engine for guiding said injector in a direction parallel to axis of the said nozzle; an engine-driven cam, tappet mechanism for actuating the plunger of said pump from said cam and including a cam follower and a tappet rod, both substantially coaxial with said plunger; a detachable head and T-slot connection between said plunger and said rod whereby said plunger and rod may be connected and disconnected by means of a sidewise relative displacement therebetween; removable retaining means for preventing said sidewise relative displacement; and resilient means in said tappet mechanism for holding said tappet rod in contact with said cam follower and the latter in contact with said cam whereby the suction stroke of said plunger is effected by said resilient means through said tappet rod.

8. In combination with an internal combustion engine, an interchangeable fuel injector therefor having a housing, a fuel delivery nozzle and a

plunger pump mounted therein transversely with respect to one another; a reciprocating mechanism for actuating the plunger of said pump; guiding means carried by said engine and cooperating with receiving means fixedly connected with said housing on opposite sides of said plunger whereby said injector is adapted to be guided in the direction of the axis of said nozzle; the axis of said plunger being centrally located between the cooperating portions of said guiding and receiving means whereby the load transmitted by said reciprocating mechanism to said plunger does not cause any appreciable deformation of said housing.

9. In combination with an internal combustion engine having a cylinder and an engine-driven cam, a fuel injector unit adapted to be detachably mounted on one side of said cylinder and including a delivery nozzle body extending transversely with the axis of said cylinder and a plunger pump directed toward said cam; a reciprocating mechanism substantially coaxial with the plunger of said pump and detachably connected therewith for actuating the latter from said cam; and centering means independent of said nozzle body for holding said injector in a predetermined position relative to said tappet mechanism corresponding to a definite injection timing without causing deflection of said nozzle body.

10. In combination with an internal combustion engine having a cylinder block and a cylinder head on said block, a gasket between said block and said head; an interchangeable fuel injector unit supported by said block and including a delivery nozzle body and a plunger pump arranged transversely with respect to said body; said nozzle body extending with radial clearance into a nozzle passage formed in said head; an engine-driven cam supported in bearings carried by said block; a tappet mechanism for actuating said pump from said cam; and means for centering said injector unit in predetermined relation to said cam and said tappet mechanism whereby changes in the relative position of said block and said head due to variations of thickness of said gasket do not affect the injection timing.

11. An interchangeable fuel injection unit adapted for detachable mounting on an engine cylinder and including a discharge nozzle valve and a plunger pump substantially at right angles, a tappet mechanism for reciprocating the plunger of said pump from an engine driven cam, and bores in said unit parallel to said valve and cooperating with positioning means carried by said cylinder for centering said unit at a predetermined distance from said cam.

12. In combination with an internal combustion engine, an interchangeable fuel injection unit including a delivery nozzle and a plunger pump mounted transversely with respect to one another; cooperating guiding means in said engine and unit whereby the latter is mounted on and removed from said engine with a translation in direction of the axis of said nozzle; reciprocal tappet means substantially coaxial with the plunger of said pump for actuating said plunger from an engine driven cam; a detachable head and T-slot connection between said tappet means and plunger whereby said plunger and tappet means are connected and disconnected by way of said translation of said unit; and resilient means connected with said tappet means for effecting the suction stroke of said plunger through said detachable connection.

13. A combination as set forth in claim 2, said injector housing means also including removable connecting means for establishing a fuel flow communication between said pump and valve, and means for clamping said connecting means on said pump and valve with sealing loads directed substantially along the axes of said pump and valve respectively.

14. In combination with an engine having a fuel injection nozzle passage, an injection unit having housing means comprising a plunger pump and a nozzle valve body removably mounted therein at right angles with respect to one another and removable connecting means for establishing a fuel flow communication between said pump and valve body; means for clamping said connecting means on said pump and valve body with sealing pressure directed substantially along the axes of said pump and valve respectively whereby no distortion of the injection unit parts occurs upon assembly thereof; and cooperating means in said engine and unit for centering and holding the latter against the operating load applied to said pump with radial clearance between said nozzle passage and valve body to prevent deflection of the latter.

15. In combination with an internal combustion engine, a fuel injection unit having housing means, a plunger pump and a nozzle valve removably mounted in said housing means transversely with respect to one another, removable connecting means in said housing means for establishing a fuel flow communication between said pump and valve, means for clamping one portion of said connecting means on said pump and another portion thereof on said valve, part of said connecting means between said portions thereof having reduced section thereby rendering the latter means adapted to yield to conform with the cooperating surfaces of said pump and valve without transmitting appreciable distorting reactions thereto, means for reciprocating the plunger of said pump, and cooperating means in said engine and unit for holding the latter at opposite sides of said plunger.

16. In combination with an internal combustion engine, an interchangeable fuel injector therefor having housing means, a nozzle valve and a plunger pump mounted therein with their axes at right angles, flexible conduit means in said housing means for leading fuel from said pump to said valve, means for clamping one end of said conduit means on said pump and the other end thereof on said valve, and cooperating means in said engine and housing means for guiding said injector in the direction of the axis of said nozzle valve.

17. In combination with an internal combustion engine, a fuel injection unit including a plunger pump and a nozzle valve arranged transversely with respect to one another, flexible conduit means in said unit for leading fuel from said pump to said valve, means for connecting said conduit means with said pump and valve, and means for securing said unit on said engine without causing distortion of said nozzle valve.

18. In combination with an engine having a cam, a fuel supply unit therefor having housing means, a cylinder and fuel pressure outlet valve means non-coaxially held by said housing means, a plunger in said cylinder actuated from said cam, flexible fuel conduit means connecting said cylinder and valve means, and means symmetrically arranged with respect to said cylinder for attaching said housing means to said engine.

19. In combination with an engine having a cam, a fuel supply unit therefor having a cylinder and fuel outlet valve means at right angles, a plunger in said cylinder actuated from said cam, two cylindrical bores formed in said unit parallel to said valve means and symmetrical with respect to said cylinder, two centering dowels carried by

5 said engine fitting into said bores to bear the operative load transmitted to said unit from said cam, and threaded clamping members also parallel to said valve means and arranged symmetrically with respect thereto for securing said unit to said engine.

FERDINANDO C. REGGIO.
